CLAIM

The ornamental design for a shaver handle, as shown and described.

DESCRIPTION

FIG. 1 is perspective view of an ornamental design for a shaver handle according to the present invention;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom side view thereof.

The broken lines illustrate portions of the shaving handle and form no part of the claimed design.
